DOOR LIFT MECHANISM

Wilfred A. Beauchamp, Chicago, Ill., assignor to
 The Youngstown Steel Door Company, Cleve-
 land, Ohio, a corporation of Ohio

Application July 30, 1943, Serial No. 496,752

5 Claims. (Cl. 16—99)

This invention relates to door lift mechanisms.

The objects of this invention are to provide lift mechanisms for sliding doors of railway house cars which shall embody relatively few, simple and inexpensive parts; reduce the number of castings required; be easily operable in either direction in a plane parallel to the door; and so reduce the overall dimension between mechanisms on opposite sides of the car that a single standard is created applicable to cars of varying widths.

Other objects of the invention will become clear as the description thereof proceeds.

In the drawing forming part of this specification:

Fig. 1 is a fragmentary elevation of a sliding car door mounted on a railway house car and equipped with a lift mechanism embodying the instant invention, parts being broken away to more clearly show the invention.

Fig. 2 is a vertical section taken on line 2—2 of Fig. 1.

Fig. 3 is a vertical section taken on line 3—3 of Fig. 1.

Fig. 4 is a horizontal section taken on line 4—4 of Fig. 1.

Referring to the drawing, a preferred embodiment of the invention is shown applied to a sliding door 10 of a railway house car. The door 10 may be of any desired construction. The one illustrated embodies a metallic panel 11 formed with a plurality of horizontal corrugations 12 and reinforced by means of front and rear vertical stiffeners 13 and 14. Adjacent its lower edge the panel 11 is offset outwardly, as indicated at 15, to form a depending flange 16 disposed substantially in the outer plane of the door. The flange 16 in conjunction with a reinforcing plate 17 and a bottom reinforcing Z-bar 18 constitute a box section for the lower portion of the door, as more clearly illustrated in Fig. 2 of the drawing. The Z-bar 18 is so disposed that one flange 19 thereof to which the backing plate 17 is secured lies behind a substantially channel-shaped door supporting track 20 which is secured in position by means of a plurality of track brackets 21 fastened as by means of rivets 22 to a channel-shaped reinforcing member 23 for an angle side sill 24. The car also embodies a threshold plate 25 supported outwardly of the side sill by means of an angle 26. The threshold plate is formed with a depending flange 27 bent outwardly to form a lip 28 lying below the flange 19 of the bottom reinforcing Z-bar 18 and cooperating therewith to

exclude snow, dust and the like and reflected light from the car.

As more clearly shown in Figs. 1 and 2 of the drawing the door in its normal lowered position is adapted to be seated directly upon the track 20 in frictional engagement therewith. In order to open or close the door, the lift mechanism of the instant invention is provided. By means of this mechanism the door is first elevated above the track and supported upon rollers and then moved in opening or closing direction.

This lift mechanism comprises a plurality of spaced roller and roller housing assemblies 29. Each assembly is disposed within the box section 15 at the lower portion of the door and embodies a pair of plates 30 and 31. A roller 32 having a roller bearing 33 is mounted between the plates in engagement with the track 20. A roller 34 disposed above the roller 32 is also mounted between the plates 30 and 31. Each of these plates beyond the rollers is offset as indicated at 35 to permit securement of the plates to a connecting bar 36, as more clearly shown in Fig. 1 of the drawing. The opposite end of each of the connecting bars 36 is disposed between and pivotally secured to a pair of ears 37 and 38, or 39 and 40, formed on an actuating member 41. The actuating member carries trunnions 42 and 43 journalled in bearing plates 44 and 45, as clearly shown in Figs. 3 and 4 of the drawing. The trunnion 43 of the actuating member is reduced in section as indicated at 46 and extended outwardly beyond the panel 11 so that an operating lever 47 may be mounted thereon. It will be observed from Figs. 1 and 4 of the drawing that a portion of the panel 11 is offset inwardly, as indicated at 48 so as to maintain the outer face of the lever within the outer plane of the door. To aid in maintaining the lever 47 on the trunnion 43 and to guide the lever in its movement the downwardly extending arcuate flange 49 of a member 50 fastened to a panel 11 cooperates with an upstanding flange 51 of a Z-shaped clip 52 secured to the inner face of the lever 47. It will be seen that the actuating member 41 lies within the box section at the bottom of the door and that the lever 47 is disposed outwardly of the door.

A plurality of members 53 are secured to the door within the box section. Each of these members is disposed above a roller and roller housing assembly 29. As more clearly shown in Figs. 1 and 2 of the drawing, member 53 is substantially Z-shaped in section and embodies an attaching flange 54, a web 55, which is inclined downward-

ly toward the center of the door, and a depending flange 56. These members are so disposed that they are adapted to be engaged by the rollers 34 of the roller and roller housing assemblies. As indicated hereinabove, the rollers 32 are adapted to engage the door supporting track 20, openings 57 and 58 being formed in the web of the Z-shaped bottom reinforcing member for this purpose.

In order to move the door the operating lever 47 is pulled in the direction in which it is desired to move the door. Movement of the lever imparts corresponding rotation to the actuating member and a pull upon the connecting bars 36. Such a pull is exerted upon the connecting bars 15 irrespective of the direction in which the lever is moved. As a result of the movement of the connecting bars 36, the roller and roller housing assemblies 29 are moved toward each other. In this movement the rollers 32 move upon the track 20 and the rollers 34 engage and roll along the underside of the webs 55 of the members 53. Due to the inclination of these webs the rollers 34 exert an upward force upon the members 53 causing the door to be lifted above the track and to be supported upon the roller and roller housing assemblies. The door can then be moved in the desired direction. When the lever is released at the end of such movement, the door will automatically lower and again seat itself frictionally upon the track.

It will be apparent from the foregoing description that the lift mechanism embodying the instant invention is very effective for its intended purpose. The members 30 and 31 of the roller and roller housing assemblies may readily be formed of plates, thereby reducing the number of castings heretofore required. The lift mechanism is double-acting and since the operating lever is maintained substantially within the outer plane of the door, the overall dimension between mechanisms on opposite sides of the car is held to a minimum so that the described mechanism may be used upon cars of different widths. A single standard lift mechanism is thereby created.

It will be apparent that numerous changes and modifications in the details of the invention will be clear to those skilled in the art. It is intended, therefore, that all such modifications and changes be comprehended within this invention, which is to be limited only by the scope of the claims appended hereto.

I claim:

1. A lift mechanism for sliding car doors comprising a plurality of spaced roller and roller housing assemblies, each of said assemblies embodying a pair of plate members, a main track engaging roller rotatably secured between said plate members and a second roller rotatably secured between said plate members above said main roller, oppositely inclined members adapted to be fastened to said door, said second rollers being engageable with said inclined members, an

actuating member adapted to be journaled in said door between said assemblies, a bar connecting each assembly with said actuating member, and a lever mounted upon said actuating member.

5 2. A lift mechanism for sliding car doors comprising a plurality of spaced roller and roller housing assemblies, each of said assemblies embodying a pair of rollers rotatably secured to a roller housing, oppositely inclined members adapted to be secured to said door, an actuating member adapted to be journaled in said door, a connecting bar extending from said actuating member to each of said assemblies, and a lever mounted upon said actuating member, said lever being operable to rotate said actuating member and impart bodily movement to said assemblies toward each other through said bars, one of said rollers of each assembly being adapted to roll upon a door supporting track and the other of said rollers to roll along under an inclined member to elevate said door during said movement of said assemblies.

10 3. In a sliding lift door for railway house cars having a box section along the lower margin thereof, spaced substantially Z-shaped members having oppositely inclined webs secured within said box section, a roller and roller housing assembly disposed below each of said Z-shaped members, each assembly embodying a pair of rollers rotatably secured to a roller housing, one of said rollers being engageable with a track for said door and the other roller being engageable with said web, and means on said door connected with said assemblies for imparting movement thereto toward each other to lift said door.

15 4. In a sliding lift door for railway house cars having a box section along the lower margin thereof, spaced oppositely inclined members secured within said box section, a roller and roller housing assembly disposed below each member, each assembly embodying a pair of rollers rotatably secured to a roller housing, one of said rollers being engageable with a track for said door and the other roller being engageable with a said member, and means on said door connected with said assemblies for imparting movement thereto toward each other to lift said door.

20 5. A lift mechanism for sliding car doors comprising a plurality of spaced roller and roller housing assemblies, each of said assemblies embodying a pair of rollers rotatably secured to a roller housing, an inclined member adapted to be secured to said door above each assembly, one of said rollers of each assembly being adapted to roll upon a door supporting track and the other of said rollers to roll along and under an inclined member to elevate said door during movement of said assemblies, and means adapted to be mounted on said door and connected with said roller assemblies for imparting bodily movement thereto.

WILFRED A. BEAUCHAMP.
